UNITED STATES PATENT OFFICE.

CHARLES M. MULLEN, OF BAKER CITY, OREGON.

ORE-SEPARATOR.

No. 923,988.

Specification of Letters Patent.

Patented June 8, 1909.

Application filed July 21, 1908. Serial No. 444,624.

To all whom it may concern:

Be it known that I, CHARLES M. MULLEN, a citizen of the United States of America, residing at Baker City, in the county of Baker 5 and State of Oregon, have invented certain new and useful Improvements in Ore-Separators, of which the following is a specification.

This invention relates to improvements in 10 ore separators and is intended more especially to be employed in sluice ways, flumes, or other conduits.

It is an object of this invention to provide 15 a device of this kind wherein the bottom of the flow passing through such flume, sluice way, or conduit is skimmed. It is a well known fact that gold, black sand or other minerals, by their weight, fall to the bottom and it is an object of the invention to separate 20 the heavier particles at the bottom of a stream passing down the sluice way, flume or other conduit without interfering with the lighter products.

It is also an object of this invention to provide 25 an adjustable slide or apron which may be regulated to compensate for the varying amounts of heavy particles carried by the stream to allow the gravel and other earth to pass over the apron to the waste dump.

With the foregoing and other objects in 30 view, the invention consists in the details of construction and in the combination and arrangement of parts to be hereinafter more fully set forth and claimed.

In describing the invention in detail, reference will be had to the accompanying drawings forming part of this specification wherein like characters denote corresponding parts in the several views, in which—

Figure 1, illustrates a side elevation of an ore separator embodying the invention; Fig. 2, is a longitudinal sectional view thereof; and Fig. 3, is a top plan view thereof with the apron omitted.

As illustrated in the drawings, 1, denotes a flume having the side walls 2, and a bottom provided intermediate its length with a transverse opening 3, beneath which is positioned the discharge spout 4. The spout is intended 50 to discharge the black sand, gold or other minerals.

Slidably arranged above the opening 3, in the bottom of the conduit is an apron 5, which is mounted on the guides 6, secured to

the opposed inner walls of the flume. It is 55 thought clearly apparent that the apron will act as a dam and that the position of the lower end thereof will regulate the discharge opening 3, and control the quantity of gold, black sand or the like which will fall within 60 the spout 4. This apron may be moved in any desired manner, but it has been found preferable to secure or position on its under surface, the rack 7, which is engaged by the pinion 8, fixed on the shaft 9, mounted in the 65 walls of the flume. One end of the shaft projects beyond a wall and is provided with a square portion 10, which may be engaged by a wrench for the purpose of turning the shaft in the desired direction.

On the shaft exterior of the flume is mounted a toothed wheel 11, which is engaged by the vertically movable latch 12, mounted in a bracket 13, secured to the outer wall of the side of the flume adjacent this 70 toothed wheel. This sliding bolt is intended to engage the toothed wheel in order that the slide or apron may be held in its adjusted position.

It is thought that the operation of this device is obvious, although it may be well to state that the stream passes down the sluice way and the lighter particles pass up over the apron and are carried to the waste discharge 85 while the heavier particles such as black sand, gold and the like pass beneath the apron and are carried off through the discharge spout 4. In order that none of these heavy particles may be lost, a block 14, is positioned a slight distance beyond the opening 90 in the bottom of the sluice way, and the lower surface of the apron slides in contact with the block, thus effectually preventing material from passing beyond said block.

I claim—

In an ore separator, a flume having an opening in the bottom thereof and inclined guideways extending along the sides of the flume from the bottom thereof at a point slightly in front of the opening, a block transversely disposed on the bottom of the flume back of the opening therein, an apron adapted to operate as a dam, said apron being slideable in the guideways and having its lower surface contacting with the upper surface of the block thereby completely closing the space between the under surface of the apron and the bottom of the flume while the apron

is in engagement with the block, said apron being located with its forward end in proximity to the discharge opening, means under the apron for sliding the same over said discharge opening to regulate the size thereof, and means for retaining the apron in adjusted position.

In testimony whereof I affix my signature in the presence of two witnesses.

CHARLES M. MULLEN.
